UNITED STATES PATENT OFFICE.

EDWIN G. VAN ZANDT, OF ST. LOUIS, MISSOURI.

GAS-BURNER.

No. 878,507.

Specification of Letters Patent.

Patented Jan. 14, 1908.

Application filed March 26, 1907. Serial No. 364,590.

REISSUED

To all whom it may concern:

Be it known that I, EDWIN G. VAN ZANDT, a citizen of the United States of America, residing in the city of St. Louis and State of Missouri, have invented certain new and useful Improvements in Gas-Burners, of which the following is a full, clear, and exact description, reference being had to the accompanying drawing, forming part of this specification.

My present invention is in the nature of an improvement upon the gas burner shown and described in U. S. Letters Patent No. 838,596, issued to me December 18, 1906, and the present invention has for its object to so construct the shell of a burner of the kind described in said patent that the heavier or heat producing elements of gas may be retained in said shell until consumed by combustion and the lighter or poisonous elements in the gas such as acetylene may be restrained from rapid escape from the shell but escape gradually therefrom in such manner as that the poisonous matter in the acetylene will be consumed by combustion at the exterior of the shell. The lighter or poisonous elements are thereby prevented from rapid dissipation in the atmosphere before they can be consumed as is the case in all other gas burning appliances of which I am aware.

Figure I is a vertical longitudinal section taken centrally through my burner. Fig. II is a vertical cross section taken on line II—II, Fig. I.

1 designates an initial burner of any suitable construction that is supported by a neck 2 into which gas passes from the conducting pipe 3 to enter and escape from said initial burner.

4 is an air inlet member surrounding the neck 2 and provided with air admission ducts 5.

The parts thus far described are to be found in the patent hereinbefore mentioned and no invention *per se* is herein claimed for them.

6 designates the shell of my burner which is supported by the air inlet member 4 and within which the initial burner is located.

This shell is of tubular form and the channel therein extends horizontally. In the upper portion of the wall of the shell is a vent 7 having the form of a V-shaped slot as seen in Fig. II.

8 are internal circular flanges at the ends of the shell which serve to contract the channel of the shell at its ends for the purpose of producing restricted end vents 9 and whereby the ends of the shell are choked to prevent inflow of air through the end vents during the operation of the burner. The inner faces or shoulders 10 of the internal flanges are so disposed that they are at the upper portion of the shell contiguous to the ends of the top vent 7, as seen in Fig. I.

In the practical use of my burner the gas to be consumed escapes from the initial burner 1 into the shell 6 and the heavier elements of the gas are consumed by combustion in the chamber or channel of said shell. These heavier elements are those from which the heat is derived in the combustion of gas and they are confined in the shell chamber, due to the top vent 7 being a restricted one and the end vents 9 being also restricted, as a consequence of which the heavier elements in their outward movement away from the initial burner strike against the longitudinal wall of the shell and against the shoulders 10 of the internal flanges 8. The lighter, poisonous elements which are given off from the gas being of less specific gravity than the heavier elements find gradual egress from the shell chamber through the top vent 7 and the end vents 9, and due to the high degree of heat at which the shell is maintained by the combustion of gas in its chamber such lighter elements are kept constantly ignited as they emerge through the top and end vents and are completely consumed before there is any possibility of their being dissipated in the atmosphere.

I claim:

A gas burner comprising an initial burner, and a shell surrounding said initial burner having internal flanges at its ends providing restricted end vents and having a V-shaped vent in the upper portion of its wall extending longitudinally of the shell and terminating at its internal flanges, substantially as set forth.

EDWIN G. VAN ZANDT.

In presence of—

E. S. KNIGHT,
LILY POST.
